(57) **CLAIM**

The ornamental design of a fuel dispenser nozzle, substantially as shown and described.

DESCRIPTION

FIG. 1 is a perspective view of a fuel dispenser nozzle embodying the design of the present invention.

FIG. 2 is a top view of the fuel dispenser nozzle illustrated in FIG. 1.

FIG. 3 is a bottom view of the fuel dispenser nozzle illustrated in FIG. 1.

FIG. 4 is a left side elevational view of a fuel dispenser nozzle of FIG. 1, the right side being a mirror image;

FIG. 5 is a front view of the fuel dispenser nozzle illustrated in FIG. 1; and,

FIG. 6 is a rear view of the fuel dispenser nozzle illustrated in FIG. 1.

The portions shown in broken lines form no part of the claimed design.
